ALBERT C. WINDAU,
Inventor

By Mason Tompkins Lawrence,
ATTORNEYS

UNITED STATES PATENT OFFICE.

ALBERT C. WINDAU, OF PORTLAND, OREGON, ASSIGNOR OF ONE-HALF TO EDWARD HILL, OF PORTLAND, OREGON.

ENGINE-STARTER.

1,281,733.

Specification of Letters Patent. Patented Oct. 15, 1918.

Application filed December 27, 1917. Serial No. 209,146.

To all whom it may concern:

Be it known that I, ALBERT C. WINDAU, a citizen of the United States, residing at Portland, in the county of Multnomah and State of Oregon, have invented certain new and useful Improvements in Engine-Starters; and I do hereby declare the following to be a full, clear, and exact description of the invention, such as will enable others skilled in the art to which it appertains to make and use the same.

This invention relates to starting mechanism for internal combustion engines and particularly to internal combustion engines arranged in vehicles.

It is one of the objects of the present invention to provide a simple, practicable, inexpensive and reliable device which may be readily installed upon the usual, manually operable starting crank shaft of engines of the type referred to.

It is a further object of the present invention to provide a starting device which may be readily associated with the usual cranking shaft of automobile engines without necessitating a permanent removal of any of the parts, and without necessitating expensive alterations to the same.

It is another object of the invention to provide a manually operable starting device, the control means of which are adapted to be disposed with relation to the seat of the vehicle occupied by the operator, so as to eliminate the necessity of the latter from leaving the car to start or crank the engine.

It is a further object of the invention to provide a device of this type which may be operated, as stated, either from a position at the operator's seat on the vehicle or which will permit the usual cranking of the engine by the ordinary crank handle provided for this purpose.

With these and other objects in view, the present invention consists in the whole, the construction, the combination and details of construction as will be more fully hereinafter described, one embodiment of the invention being illustrated in the accompanying drawing, in which:

Figure 1 is a front side elevation, partly in section, of the starting sector,

Fig. 2 is a plan view of the cranking shaft and its associated elements, partly taken in

section on the plane indicated as line 2—2 of Fig. 1,

Fig. 3 is a perspective view of the starting mechanism as installed on a vehicle, the body of which is illustrated in dotted lines,

Fig. 4 is a side elevation in detail and partly broken away, of the trip mechanism, and

Fig. 5 is a detail plan view of one of the connections.

While in the present disclosure, the invention is shown as designed as readily applicable to automobiles of the Ford type, it is to be understood that the various elements may be varied in shape, design and in other details as may be necessary to accommodate it to engines of different types or for other purposes, as may be desired.

In the drawings, 1 represents one of the usual clutch members of vehicles of this type, this member being secured to a shaft 2 having a crank 2^a at its outer end whereby the shaft may be turned by this means when desired. Rotatively mounted on the inner end of the shaft is a segment of a sleeve 3 on which is pivoted a pawl 4 adapted to engage a ratchet 5 fixed on the end of the shaft, so that the latter may be rotated in one direction of movement of the segmental sheave, the ratchet being designed to play freely over the seat when moving in the opposite direction. A spring 3', connected at one end to the segment 3 is adapted to be connected at its other end to any suitable support has the function of returning the segment to its idle position, and connected to 85 and extending tangentially from the sheave is a section of chain 6 or any other suitable element which is fastened to the larger end of a multiplying pulley wheel 6', Fig. 3, from the smaller wheel or end 6^a of which 90 there extends a chain which is connected to a segment 8 of a manually operable lever arm or lever 9, disposed adjacent the operator's seat in the vehicle.

The shaft 2 is held yieldingly in a forward or outermost position to disengage the clutch member 1 from its complementary element by means of a spring 10, reacting against a collar or shoulder 10' on the shaft, this latter being engaged by a lever 11 which 100 is flexibly connected to a convenient portion of the frame or other support by a chain 11'; for instance, the lever having at

its other end a connecting rod 12 which is connected at its opposite end to a bracket or other suitable device 13^b secured on or attached to a trip arm 13 which is pivoted at 5 13^a on a slide 13^c appropriately supported on a portion of the frame of the vehicle or of a device secured thereto.

- It is desirable to provide means whereby the cranking shaft 2 can be shifted axially 10 so as to carry its clutch 1 into driving association with its coöperative member, not shown, and then to rotate the shaft 2 so as to turn over the crank shaft of the engine. It is especially desirable that these two functions be obtained by the use of a single element, for instance, as the control lever 9 for the simplification of the parts and ease of operation, and therefore, the trip arm 13 is shown as having a shoulder engaging a complementary pawl or interlocking device 14 connected at 14^a to the draw chain 7, above described, the actuating lever 14 being shown as guided between suitable antifriction devices as rollers 16 and 17.
- 25 In operation, when the lever 9 is thrown forwardly, for instance, it pulls the chain 7, and through it the connecting rod 14, which at this time, is engaged by the forward end of the pawl or trip 13 which is pressed 30 downward by a spring 12^a, until the forward inclined end of the lever 13 engages a pin 15 which causes the elevation of the lever or pawl 13, and its disassociation from the member 14 whereupon the spring 10 acts 35 automatically to tend to push the shaft 2 forwardly for the ready separation of the clutch member 1 as necessary. However, after the initial forward movement of the shaft 2 through means of the trip pawl 13, 40 further movement of the lever 9 acts through the chain 7 and the multiplying device 6', and the chain 6 connected to the sector 3 to rotate the crank shaft and thus start the engine while the clutches are engaged. As soon 45 as the engine picks up speed, the clutches are automatically disengaged through the action of the spring 10, which throws the shift lever 11 forwardly, and with it the connecting rod 12.
- 50 What is claimed is:
1. A starting device for combustion engines comprising a starting shaft, means for normally holding said shaft in an inoperative position, means for actuating said shaft, and automatically releasable trip mechanism connecting said starting shaft and shaft actuating means for a predetermined distance of movement of said shaft actuating

means for shifting said starting shaft into operative position.

2. A starting device for combustion engines comprising a starting shaft, a manual lever, means for rotating the shaft operable by said lever, and automatically releasable trip mechanism connecting said starting 65 shaft and shaft actuating means for a predetermined distance of movement of said shaft actuating means for shifting said starting shaft into operative position.

3. A starting device for combustion engines comprising a starting shaft, means for normally holding said shaft in an inoperative position, means for rotating the shaft, mechanism connected to said shaft rotating means for a portion of its actuating movement, and means for disconnecting the mechanism at a predetermined point during the movement of said starting means.

4. A starting device for combustion engines comprising a starting shaft with a ratchet, means for normally holding the shaft in inoperative position, a sector pivoted on the shaft and having means to engage the ratchet, a starting lever connected to the sector, and automatically releasable trip mechanism connecting with the shaft actuating devices for a portion of their movement for shifting the said shaft into operative position.

5. A starting device for combustion engines comprising a starting shaft with a ratchet, means for normally holding the shaft in inoperative position, a sector pivoted on the shaft and having means to engage the ratchet, a starting lever connected to the sector, and automatically releasable trip mechanism connecting with the shaft actuating devices for a portion of their movement for shifting the said shaft into operative position, the shaft being rotative independently of the starting means.

6. A starting device for combustion engines comprising a starting shaft, means for holding it in inoperative position, means for rotating said shaft, and mechanism for shifting the shaft to operative position comprising a shift lever engaging a part on the shaft, self-connecting trip elements one of which is connected to said shaft rotating means and the other to said lever, and means for automatically tripping said elements after the shaft has been moved to operative position.

In testimony whereof I affix my signature.

ALBERT C. WINDAU.
